UNITED STATES PATENT OFFICE

WILLIAM ROBERT CLUFF, OF NEW YORK, N. Y.

DESIGN FOR A GAME BOARD

Application filed December 4, 1931. Serial No. 41,965. Term of patent 14 years.

To all whom it may concern:

Be it known that I, WILLIAM ROBERT CLUFF, a subject of the King of Great Britain, residing in the city, county, and State of New York, have invented a new, original, and ornamental Design for a Game Board, of which the following is a specification, reference being had to the accompanying drawing, forming a part thereof.

The figure is a plan view of a game board showing my new design. The design has no appreciable depth or thickness, being intended to be applied to a flat surface, such as the top of a table or a game board or a flexible covering for a game table.

I claim:

The ornamental design for a game board as shown and described.

WILLIAM ROBERT CLUFF.
